UNITED STATES PATENT OFFICE.

DARLINGTON C. WATSON, OF SCAMMON, KANSAS, ASSIGNOR OF ONE-HALF TO CHRISTIAN U. BENDER, OF SCAMMON, KANSAS.

MERRY-GO-ROUND.

Application filed November 1, 1924. Serial No. 747,280.

This invention relates to an amusement device, the general object of the invention being to provide a plurality of cars with means for causing the cars to travel in a circular path and at the same time to move back and forth in a radial path so as to give the occupants the effect of traveling in a zig-zag path.

Another object of the invention is to so 10 arrange the parts that the device can be controlled by a single operator and with means whereby the operator can raise and lower a cover on each car.

To the attainment of the foregoing, the 15 invention resides in the improvement as hereinafter described and definitely claimed.

In the drawings:

Figure 1 is a plan view of a portion of the 20 device.

Figure 2 is an enlarged transverse sectional view and showing one car.

Figure 3 is an enlarged sectional view showing the means for mounting the guiding pulleys for the top operating cables.

Figure 4 is a sectional view through one 25 of the car engaging rollers.

Figure 5 is a sectional view through one of the cars and its operating means.

Figure 6 is an enlarged plan view with a 30 car removed and showing the arrangement of parts under the car.

Figure 7 is a detail view of a part of the top operating means.

Figure 8 is a bottom plan view of the hub 35 and portions of the sweeps.

Figure 9 is a vertical sectional view through the central supporting post and the hub.

Figure 10 is a detail view of the drive 40 means for the device.

Figure 11 is a view of the brake mechanism for the motor.

Figure 12 is a fragmentary view of a portion 45 of the track.

In these views 1 indicates the central supporting post which is provided with the base 2 and which is of tubular construction. A collar 3 is fastened to the post and carries a race for the balls 4 which are engaged by a race formed on the under face of the hub member 5. This hub member is provided with the depending ears 6 which are arranged in pairs around its periphery and the radiating sweeps 7 are pivoted to these ears so that the sweeps have a limited move-

ment in a vertical plane. An annular frame 8 is fastened to the outer ends of the sweeps and the sweeps are connected together by the braces 9 which have slots 10 therein for receiving the bolts 11 which fasten them to the sweeps so that these braces permit the sweeps to move in a vertical plane. The frame 8 carries a plurality of pairs of supporting bars 12, each pair supporting a car 13, each car having brackets 14 on its bottom which are formed with openings 15 through which the bars 12 pass so that the cars are locked to the frame but can have sliding movement thereon. Rollers 16 are supported by the roller bearings 17 on the stub shafts 18 carried by the bars 12 and engage the bottom of the cars to reduce friction in the movement of the cars. A shaft 19 is journaled in the frame 8 under each car and a wheel 20 is fastened to each shaft 25 and engages an annular track 21 placed upon the ground under the frame so that the outer portion of the device is supported from this track. Each shaft 19 is connected by the gears 22 with a shaft 23 journaled in the frame 8 under each car and a cam disk 24 has its hub 25 fastened to the shaft 19. This disk engages a channel-shaped bracket 26 on the bottom of each car so that as the disk rotates it will engage first one flange of the bracket to force the car sidewise in one direction and then it will engage the other flange to move the car in another direction. Thus the cars will be reciprocated sidewise and in a radial direction as the entire device is being rotated around the central post.

The device is rotated through means of the cable 27 which is wrapped around a drum 28 and passes around the friction blocks 29 on the outer ends of the sweeps 95 so that as the drum is rotated the frictional engagement of the cable with the blocks will cause the entire device to rotate around the post with the wheels 20 engaging the track so that the device is supported at its center and its periphery and the movement of these wheels will be communicated to the cars to reciprocate the same. Each block 29 is provided with a groove 30 in its outer edge for receiving the cable and a strip 31 of metal extends beyond the grooved part and forms a seat for a part of the cable. The drum is arranged on a vertical stub shaft 32 which is connected by the bevel gears 33 with a small shaft 34, this shaft 105

carrying a pulley 35 which is engaged by a belt 36 which also engages a pulley on the shaft of a motor 37. The motor is provided with a brake 38 and the pulley is connected with the motor shaft by a clutch which is operated by a bell crank 39 and both the bell crank and the brake are adapted to be actuated from a point adjacent the post 1 by the rods 40 which are rotatably arranged in the post and which have handles 42 at their upper ends and the lower ends are connected with the bell crank and brake by the connections 43. Thus a single operator can manipulate the clutch to control the drive of the device from the motor and to brake the motor.

I also provide a movable top 44 for each car or carriage, the top being attached to a shaft 45 which has the pulleys 46 at its ends. A shaft 47 is journaled in the frame 8 adjacent each carriage and each shaft has a sleeve 49 keyed thereto so that the sleeve can slide on the shaft. A pair of pulleys 50 are fastened to each sleeve and these pulleys are belted to the pulleys 46 by the belts 51. Thus when the shaft 47 is rotated the shaft 45 will also be rotated so that the top will be moved to closed position or to open position according to the direction of movement of the shaft. By having the pulleys 50 mounted on a sleeve which is slideable on the shaft 47, the pulleys can move with the car. This will prevent the top operating means from interfering with the reciprocation of the cars. The tops are operated simultaneously by the operator at the central station through means of the drum 52 fastened to the lower end of a shaft 53 rotatably mounted in the hub and having a handle 54 at its upper end, the cable 55 which is

wrapped around the drum 52 and after passing around the guide pulleys 56 is fastened to the arms 57 which are connected with the ends of the shafts 47. Thus by turning the drum 52 in one direction the cables attached to the arms 57 will rock the shafts 47 to open the tops and by turning the drum in an opposite direction the shafts will be rocked to close the tops.

The track comprises a base 58 and the metal strips 59 fastened to the base and the base is connected with the base 2 of the central post by the cables 60 which are provided with the turn buckles 61. The track is formed in sections so that it can be laid on uneven ground.

From the foregoing it will be seen that the occupants of the cars will move in a zig-zag circular path as the cars will be reciprocated sidewise and radially as they are being moved in a circular path. By having the sweeps hinged to the hub and movably attached to the braces the device can be erected on uneven ground as well as on level ground, as the parts will conform themselves to the conformation of the surface on which they are placed.

What I claim is:—

An amusement device including a frame, radial tracks carried by the frame, cars 70 slidably mounted on said tracks, means for imparting sliding movement to said cars, a shaft having its ends journaled on the frame, spaced pulleys carried by the shafts, movable tops for said cars, means movably connecting the pulleys with said tops and means whereby to impart movement to the shaft for actuating said tops relative to the cars.

In testimony whereof I affix my signature.
DARLINGTON C. WATSON.
